UNITED STATES PATENT OFFICE

JOHN H. PHILLIPS, OF CHICAGO, ILLINOIS

ANCHORING APPARATUS

Application filed July 13, 1925. Serial No. 43,329.

This invention relates broadly to anchoring apparatus and particularly to anchoring apparatus comprising anchoring devices which are expanded or otherwise secured to 5 or in a wall or the like. The invention has among its other objects the production of anchoring apparatus which is extremely neat and attractive in appearance, compact, convenient and satisfactory for use wherever 10 found applicable. A particular object of the invention is to provide improved anchoring apparatus which can be properly secured in a wall or ceiling in a minimum amount of time, the apparatus being assembled while 15 it is being installed.

In one embodiment of the invention, an anchor shell having drill teeth at one end and a taper seat at the other end is seated in a chuck and then driven into a ceiling to 20 form a cylindrical hole therein. The shell is then withdrawn from the cylindrical hole and a tapered plug is inserted in the drilling end thereof, after which it is again driven into the hole to be expanded therein. The 25 chuck is then removed from the tapered end of the shell and a collar or ceiling plate having an aperture therethrough is positioned upon the taper seat formed on the shell. The chuck is then employed to drive the collar or 30 ceiling plate on the shell until it is firmly seated thereon.

Many other objects and advantages of the construction herein shown and described will be obvious to those skilled in the art from the 35 disclosure herein given.

To this end my invention consists in the novel construction, arrangement and combination of parts herein shown and described, and more particularly pointed out in the 40 claims.

In the drawings, wherein like reference characters indicate like or corresponding parts:

Fig. 1 is a central section through an anchoring device and a chuck, the chuck being employed to mount the shell in a spring handle or the like;

Fig. 2 is a section taken on substantially the same line as Fig. 1, but showing the anchoring device expanded in a ceiling;

Fig. 3 is a section taken on substantially the same line as Figs. 1 and 2, but showing a collar or ceiling plate assembled with the anchoring device;

Fig. 4 is an enlarged central section taken 55 through the collar or ceiling plate shown in Fig. 3; and

Fig. 5 is a central section through a collar or ceiling plate embodying another form of my invention.

Referring for the present to Fig. 1, the reference character 10 designates generally an anchoring device which may be of any desired size and form, but which in this instance is tubular and is provided with drill teeth 11 at one end thereof. The other end of the anchoring device 10 is externally tapered as 60 at 12, the tapered end of the anchoring device being internally threaded as at 13 for a purpose which will presently appear.

The anchoring device 10 is provided with a plurality of slots 15 which form weakened portions 16 adjacent the drill teeth 11. The anchoring device 10 is shown in connection with a chuck 18 which is provided with a tapered recess 19 adapted to accommodate the taper seat 12 formed upon the device 10. In practice, the chuck 18 is properly secured 65 in a spring hammer or the like whereby the anchoring device 10 may be subjected to a 70 series of blows. When so driven into the ceiling 20, the anchoring device 10 forms a cylindrical hole 22 therein. After the cylindrical hole 22 has been formed in the ceiling 20 the anchoring device is withdrawn therefrom 75 and a tapered plug 24 is seated in the drilling end thereof (Fig. 2). The anchoring device 10 is again driven into the hole 22 by means of the spring hammer. During the second 80 drilling operation, the tapered plug 24 expands the drilling end of the anchoring device 10 and the drill teeth 11 enlarge the bottom of the cylindrical hole 22 as indicated at 85

25. Generally the weakened portions 16 are fractured during the second drilling operation.

After the anchoring device 10 has been expanded in the ceiling 20, the chuck 18 is withdrawn therefrom and a collar or ceiling plate 27 is slipped over the taper seat 12, the 90 95 100

collar or ceiling plate 27 being provided with an aperture 28 which is preferably tapered to correspond with the taper of the seat 12. The chuck 18 is then employed to drive the collar or ceiling plate 27 upon the taper seat 12 until a press or force fit is obtained between the device 10 and the collar or ceiling plate 27, the arrangement being such that the collar or ceiling plate 27 may be brought into a position wherein it contacts with the ceiling 20 to conceal the outer edge of the cylindrical hole 22. This gives a neat and attractive appearance to the anchoring apparatus. Apparatus may be suspended from the anchoring device by means of a rod (not shown) or the equivalent threaded into the screw threads 13.

In Fig. 5 I have shown a collar or ceiling plate 30 which embodies another form of the invention, the collar or ceiling plate 30 being substantially cup-shaped in form and is provided with an aperture 31 which is preferably tapered to correspond with the taper of the seat 12.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. The combination with an anchoring device adapted to be embedded in a wall, or the like, and provided with a tapered end adapted to project from the wall, of an apertured member forcibly driven onto said tapered end to conceal the joint between said device and the wall, said member being adapted to be assembled with said device after the device has been embedded in the wall.

2. The combination with an anchoring device having a tapered portion engageable by a chuck whereby the anchoring device may be driven into a wall, or the like, to have the tapered portion project therefrom, of an apertured member adapted to be forcibly driven onto said tapered portion by the chuck to conceal the joint between the anchoring device and the wall.

3. A method of assembling anchoring apparatus comprising seating an anchoring device in a chuck, employing the chuck to drive the anchoring device into a wall, or the like, withdrawing the chuck from the anchoring device, and then employing the chuck to drive an apertured plate onto the anchoring device.

4. A method of assembling anchoring apparatus comprising seating an anchoring device in a chuck, employing the chuck to drive the anchoring device into a wall or the like, to form a hole therein, removing the anchoring device from the wall, placing a tapered

plug in one end thereof, employing the chuck for driving the anchoring device into the wall for the second time, removing the chuck from the anchoring device, and employing the chuck to drive an apertured plate onto the anchoring device.

In testimony whereof, I have hereunto signed my name.

JOHN H. PHILLIPS.
